UNITED STATES PATENT OFFICE.

JOHN T. UNDERWOOD, OF BROOKLYN, NEW YORK.

DESIGN FOR A BOTTLE.

SPECIFICATION forming part of Design No. 16,712, dated May 25, 1886.

Application filed February 13, 1886. Serial No. 194,042. Term of patent 7 years.

To all whom it may concern:

Be it known that I, JOHN T. UNDERWOOD, a citizen of the United States, residing at Brooklyn, in the county of Kings and State 5 of New York, have invented and produced a new and original Design for Bottles, of which the following is a specification, reference being had to the accompanying drawings, forming part thereof.

10 Figure 1 is an external side view with a stopper, and Fig. 2 is a plan without a stopper, of my design for bottles.

The leading features of my design consist in the general contour of the bottle, combined 15 with a flared mouth provided with a lip, and a series of ornamental designating rings formed on the base of the neck of the bottle, and a stopper.

20 A represent the external contour of the bottle; B, the neck, and C the flared mouth, which is formed with a lip, D. Around the base of

the neck B are arranged a series of projecting rings, E.

My design for bottles has a stopper, F.

What I claim as new, and desire to secure 25 by Letters Patent, is—

1. The design for bottles having a contour, A, embodying a neck, B, flared mouth C, and lip D, combined with a series of projecting rings, E, arranged around the base of the neck 30 B, substantially as shown and described.

2. The design for bottles having a contour, A, embodying a neck, B, flared mouth C, lip D, and a series of projecting rings arranged around the base of the neck B, and a stopper, 35 F, substantially as shown and described.

In witness whereof I have hereunto set my hand this 13th day of February, 1886.

JOHN T. UNDERWOOD.
